UNITED STATES PATENT OFFICE.

FRED HAYS, OF ASSUMPTION, ILLINOIS.

WIRE-STRETCHER.

1,131,061.

Specification of Letters Patent.

Patented Mar. 9, 1915.

Application filed September 10, 1914. Serial No. 861,107.

To all whom it may concern:

Be it known that I, FRED HAYS, a citizen of the United States, residing at Assumption, in the county of Christian and State of Illinois, have invented certain new and useful Improvements in Wire-Stretchers, of which the following is a specification, reference being had to the accompanying drawings.

This invention relates to certain improvements in wire stretchers, and the object of the invention is to provide a device of this general character having novel and improved means whereby the wire to be stretched may be effectively clamped, especially when such wire comprises a plurality of strands, as employed in a fence structure.

The invention consists in the details of construction and in the combination and arrangement of the several parts of my improved wire stretcher whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be better understood, I will now proceed to describe the same with reference to the accompanying drawings, wherein—

Figure 1 is a view, partly in elevation and partly in section, of a clamp constructed in accordance with an embodiment of my present invention; Fig. 2 is a fragmentary front elevational view of the device as disclosed in Fig. 1; Fig. 3 is a fragmentary elevational view taken from the side opposite to that shown in Fig. 2; Fig. 4 is a view in top plan of my complete wire stretcher; Fig. 5 is a central fragmentary view partly in plan and partly in section illustrating in detail the means herein embodied for imparting movement to the wedge member.

As disclosed in the accompanying drawings, 1 denotes an elongated strip of material provided at one extremity with an extension 2, said extension being of less thickness than the thickness of the body 1. I find in practice that it is particularly advantageous to have the body 1 formed of wood.

The body 1 serves as the center member of the clamp included in my improved wire

stretcher, and coacting with one face thereof is the outer member 3 provided with a plurality of longitudinally aligned spaced slots 4, one extremity 5 whereof being enlarged for a purpose to be hereinafter set forth, and the slots 4 are adapted to register with the opening 6 produced in the body 1. The outer member 3 is adapted to coact with the body 1 to clamp the wire therebetween, such clamping action being attained in a manner which will be hereinafter fully set forth.

Disposed through the aligned slots 4 and openings 6 are the bolts 7 the heads whereof being capable of ready insertion through the enlarged portions 5 of the slots 4, whereby it will be readily perceived that the member 3 may be applied in operative position upon the body 1 in a convenient and effective manner. The opposite extremities of the bolts 7 are directed through the elongated longitudinally disposed slots 8 produced in the wedge member 9 adapted to engage the opposite face of the body 1 and having coacting with the inclined faces or wedges 10 the nuts 11, whereby it will be perceived that upon movement of the wedge member 9 in one direction requisite clamping tension may be imposed upon the clamping member 3. The wedge member 9 is of a length to project slightly above the extremity of the body 1 provided with the extension 2.

Overlying the inner face of the extension 2 is the rack plate 12 anchored thereto by the medium of the bolts 15 and said rack plate is adapted to be engaged by the pinion 16 rotatably supported in the frame 17 connected to the block 18 removably secured to the upper extremity of the wedge member 9, whereby the frame 17 and its concomitant parts may be readily removed from operative position when the necessities of practice may so require.

Pivottally engaged with the trunnions 19 of the pinion 16 and straddling the same is the forked member 20 provided in its base portion with an opening 21 through which projects the operating lever 22. Said lever 22 is provided with a head 23 engageable with the teeth of the pinion 16 whereby the requisite axial rotation may be imparted thereto in order to impart the requisite movement to the wedge member 9, and in order that the head 22 may be disengaged from the teeth of the pinion so as to permit the requisite oscillation of the lever it is to

be observed that the inner extremity of the opening 21 is enlarged to receive the head 23, whereby the requisite longitudinal movement may be imparted to the lever 22. The head 23 of the lever is adapted to normally engage the teeth of the pinion and in order to maintain this normal engagement I employ the expansible member 24 surrounding the lever 22 and interposed between the head 23 thereof and the base of the enlarged portion of the opening 21 and operating in a manner which is believed to be self-evident. I find it of advantage in practice to interpose between the wedge member 9 and the body 1 the wear plate 25 provided with suitable openings through which the bolts 7 may be directed. One side of the body 1 has in swiveled engagement therewith the hook member 26 that affords a means whereby the flexible member 27 of the stretcher proper may be engaged. While I particularly disclose hooks 26 I do not wish to be understood as limiting myself in this exact particular as any other means which will operate with equal facility may be employed.

The wire stretcher proper as herein disclosed comprises the elongated member 28 provided with a longitudinally disposed elongated slot 29 and having its opposite margins intermediate the length thereof provided with the notches 30, and one extremity of the member 28 has suitably secured thereto a flexible member 31 adapted to be engaged with a stationary support or the like, so that the desired pull upon the clamp hereinbefore described may be effected. Coacting with the elongated member 28 is a slide 32 with which the flexible member 27 hereinbefore referred to is engaged. Said slide is also provided at opposite sides of the elongated member 28 with the extensions 33 with which are pivotally engaged the plates 34 projecting from opposite sides of the lever 35. The plates 34 extend entirely across the elongated member and at opposite sides of said member are provided with the U-shaped dogs 36 pivotally engaged with the plates 34 and adapted to coact with the notches 30 in a manner and for a purpose which is believed to be self-evident. In order to insure such engagement of the dogs 36 I interpose therebetween the retractable member 37 herein disclosed as a coiled spring having its opposite extremities suitably secured to the dogs 36.

From the foregoing description, it is thought to be obvious that a wire stretcher constructed in accordance with my invention is of an extremely simple and comparatively inexpensive nature and is particularly well adapted for use by reason of the convenience and facility with which it may be assembled, and it will also be ob-

vious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A device of the character described including a wire clamp comprising a body, a clamping plate overlying one face of the body, a wedge plate overlying the opposite face of the body, said clamping plate and wedge plate being provided with elongated longitudinally disposed slots, means carried by the body disposed through the slots of the clamping plate and wedge plate and serving as a tensioning means, a rack carried by an extremity of the body, a frame detachably engaged with an extremity of the wedge member and overlying the rack on the body, a pinion rotatably supported by the frame and adapted to mesh with the rack, and means for imparting axial rotation to the pinion.

2. A device of the character described including a wire clamp comprising a body, a clamping plate overlying one face of the body, a wedge plate overlying the opposite face of the body, said clamping plate and wedge plate being provided with elongated longitudinally disposed slots, means carried by the body disposed through the slots of the clamping plate and wedge plate and serving as a tensioning means, a rack carried by an extremity of the body, a frame detachably engaged with an extremity of the wedge member, a pinion provided with trunnions whereby the pinion is rotatably engaged with the frame, a forked member straddling the pinion and pivotally engaging the trunnions thereof, said forked member being provided in its base portion with an opening, and an operating lever projecting from the opening and engageable with the pinion, said lever being capable of longitudinal movement relative to the pinion.

3. A device of the character described including a wire clamp comprising a body, a clamping plate overlying one face of the body, a wedge plate overlying the opposite face of the body, said clamping plate and wedge plate being provided with elongated longitudinally disposed slots, means carried by the body disposed through the slots of the clamping plate and wedge plate and serving as a tensioning means, a rack carried by an extremity of the body, a frame detachably engaged with an extremity of the wedge member, a pinion provided with trunnions whereby the pinion is rotatably engaged with the frame, a forked member straddling the pinion and pivotally engaging the trunnions thereof, said forked mem-

ber being provided in its base portion with an opening and an operating lever projecting from the opening and engageable with the pinion, said lever being capable of longitudinal movement relative to the pinion, and means for normally maintaining the lever in engagement with the pinion.

In testimony whereof I hereunto affix my signature in the presence of two witnesses.

FRED HAYS.
